A. L. RUTHVEN

INSULATED RAIL JOINT

Original Filed Sept. 6, 1921

FIG. 2.

Inventor:
A. L. RUTHVEN,
By *Monroe S. Miller*
Attorney.

UNITED STATES PATENT OFFICE.

ALFRED L. RUTHVEN, OF ROCHESTER, NEW YORK.

INSULATED RAIL JOINT.

Original application filed September 6, 1921, Serial No. 498,609. Divided and this application filed November 30, 1921. Serial No. 518,870.

To all whom it may concern:

Be it known that I, ALFRED L. RUTHVEN, a citizen of the United States, residing at Rochester, in the county of Monroe and 5 State of New York, have invented certain new and useful Improvements in Insulated Rail Joints, of which the following is a specification, reference being had therein to the accompanying drawing.

10 The present invention relates to insulated rail joints for use in railway signalling or train controlling apparatus, and this application is a division of the copending application for patent on simplex train control 15 filed September 6, 1921, Serial No. 498,609.

The object of the invention is to provide a novel and improved insulated joint for the traffic rails, in order to obtain insulation which will not break down, as well as efficiently supporting the rail ends and preventing the rail sections from creeping.

With the foregoing and other objects in view, which will be apparent as the description proceeds, the invention resides in 25 the construction and arrangement of parts, as hereinafter described and claimed, it being understood that changes can be made within the scope of what is claimed, without departing from the spirit of the invention.

30 The invention is illustrated in the accompanying drawings, wherein—

Figure 1 is a side elevation showing the improved insulated rail joint.

35 Fig. 2 is an enlarged section on the line 2—2 of Fig. 1.

Fig. 3 is a side elevation of a modified form of insulated rail joint.

One form of insulated rail joint is shown 40 in Figs. 1 and 2, wherein the insulating plates or sheets 90 are disposed between the adjacent ends of the rail sections 91, and fish plates or bars 92 of wood or other insulating material are secured to the opposite 45 sides of the rail webs by means of the usual bolts 93. Said fish bars are sufficiently stout to assist in holding the rail sections together in alinement. Two pairs of side plates 94 are secured by the bolts 93 to the 50 bars 92, and the adjacent ends of said plates are spaced apart so as to be insulated from one another, with only the bars 93 extending from one rail section to the other across the insulation between the rail sections. The

plates 94 have lower turned flanges 95 to 55 extend under the base flanges of the rail sections, and the flanges 95 of the two pairs of clamping plates have depending abutments 96 disposed at opposite sides of the tie 97 which is disposed under the joint. Angle plates 98 are preferably fitted on the tie over the upper corners thereof so that the flanges 95 and abutments bear against said plates, as seen in Fig. 1. The abutments 96 of each pair are secured together by transverse bolts 99 extending through them, and the abutments are secured to the tie 97 at the opposite sides by means of lag screws 100 extending through the abutments and into the tie. The abutments are thus firmly 60 secured to the tie, which will fasten the rail sections down on the tie, and also prevent the creeping of the rail joint on the tie. The tie 97 is supported on a concrete sleeper or base 102 embedded in the roadbed, said 65 sleeper or base having an upper groove or channel 101 receiving the tie, to retain the tie in place. Bars or shims 103 of wood or other suitable material are disposed in the channel 101 under the tie 97, for cushioning the tie and also supporting it at the desired height in either horizontal or inclined position according to the track. A plate 104 of insulating material is disposed 70 under the ends of the rail sections on the tie 97 between the flanges 95, and is held in place by lugs 105 extending from the adjacent ends of said flanges and overlapping the ends of said plate 104. With this construction, there is no metal extending from 75 one rail section to the other, and the parts 90, 92, 97 and 104 between the rail sections 80 are all of insulating material, so that the insulation will not break down. The joint 85 is also firmly supported and is prevented from creeping.

A modified form of insulated rail joint is shown in Fig. 3, wherein the end portions of the rail sections 91 are disposed on the concrete sleeper or base 102' which has channels or grooves 101' extending transversely under the rail sections with cushion bars or plates 103' disposed in said channels. The base flanges are clamped down on the bars 103' by means of clamps 94' engaged by 100 bolts 100' embedded in the sleeper 102', thereby fastening the rail sections down,

Abutments 96' are clamped to the rail sections and abut the opposite sides of the sleeper 102', to prevent the rail from creeping.

5 Having thus described the invention, what is claimed as new is:—

1. An insulated rail joint comprising spaced clamps for the end portions of the rail sections having portions to extend under the base flanges of the rails and abutments below said portions to abut the opposite sides of a support on which said portions are disposed.

10 2. An insulated rail joint comprising spaced clamps for the end portions of the rail sections, each clamp having opposite side members with portions to extend under the base flanges of the corresponding rail section, said portions having depending 40 abutments to abut a support on which said portions are disposed.

15 3. An insulated rail joint comprising spaced clamps for the end portions of the rail sections, each clamp having opposite side members with portions to extend under the base flange of the corresponding rail section, said portions having depending 45 abutments to abut a support on which said portions are disposed, said abutments of 50 each clamp being secured together.

4. An insulated rail joint comprising fish bars of insulating material to fit the opposite sides of the end portions of the rail sections, and clamps at the outer sides of said fish bars to engage the base flanges of 35 the rail sections and adapted to be secured on a support, said clamps of the two rail sections being spaced apart.

5. An insulated rail joint comprising fish bars of insulating material to fit the opposite sides of the end portions of adjacent rail sections, and spaced clamps to be secured to the rail sections at the outer sides of the fish bars, with the fish bars clamped between the clamps and rail sections, said 45 clamps being formed to be secured on a support.

6. An insulated rail joint comprising fish bars of insulating material to fit the sides of the end portions of two adjacent rail 50 sections, and spaced clamps to engage the base flanges of the rail sections at the outer sides of said fish bars, said clamps being adapted to be secured on a support and having abutments to abut opposite sides of 55 the support.

In testimony whereof I hereunto affix my signature.

ALFRED L. RUTHVEN.
